PACKAGE OF SAFETY PINS

Clifford E. Stubbs, Weston, Mass., assignor to The Reddy Company, Inc., Montpelier, Vt., a corporation of Vermont

Application June 3, 1955, Serial No. 36,358

Term of patent 14 years

(Cl. D58—2)

Fig. 1.

Fig. 2.

Fig. 3.

Fig. 1 is a top plan view of a package of safety pins embodying my new design;

Fig. 2 is an edge elevational view thereof; and

Fig. 3 is a cross-sectional view thereof, taken on the line 3-3 of Fig. 1.

The cover portion of the package is shown partially broken away in Fig. 1, the package being lined to represent contrasting colors of the underneath layer at the center portion thereof, and of the upper layer surrounding the center portion thereof.

I claim:

The ornamental design for a package of safety pins, substantially as shown and described.
